UNITED STATES PATENT OFFICE,

JAMES GREER, OF KEARNEY, NEW JERSEY.

IGNITER FOR INFLAMMABLE LIQUIDS.

1,189,683.

Specification of Letters Patent.

Patented July 4, 1916.

Application filed September 19, 1914. Serial No. 862,452.

To all whom it may concern:

Be it known that I, JAMES GREER, a citizen of the United States, residing at Kearney, in the county of Hudson and State of New Jersey, have invented a new and useful Improvement in Igniters for Inflammable Liquids, of which the following is a specification.

This invention relates to igniters or burners used in connection with cans from which a volatile inflammable liquid is set afire as it is poured out. Cans provided with such burners or igniters are used for removing ice and snow from switches and man hole covers and for other purposes.

The object of this invention is to provide an igniter or burner by which the stream of liquid issuing from the same is thoroughly ignited before falling upon the ice, snow or other object and which insures the complete combustion of the liquid so that no part of the same is lost or wasted, and further to render such igniter or burner simple in construction and effective and safe in use.

In the accompanying drawings: Figure 1 is an elevation of a can provided with this improved igniter. Fig. 2 is a vertical longitudinal section of the igniter, on an enlarged scale. Fig. 3 is an end view and Fig. 4 is a plan view of the same.

10 represents the can which may be of any suitable construction and is provided near its bottom with a pouring pipe or spout 11 which extends in a substantially horizontal direction from the can. This pipe is provided near the can with a check valve 12 for preventing backward flow of the liquid and with a stop cock 13. The can is provided with a handle 14 which preferably extends 20 forwardly beyond the can and is connected with the pouring pipe by an oblique brace 15.

The igniter or burner is secured to the discharge end of the pouring pipe in any suitable manner and comprises an elongated chamber 16 having between its ends a raised portion 17 and at its front end a well 18 adapted to receive a wick of asbestos or other suitable material. The top plate of the front portion of the igniter is provided 30 above the well with a short depending collar 19 in which the wick is seated. The front portion of the igniter comprising the well and wick tube forms a pilot lamp which is kept filled with the liquid and which maintains a constant pilot flame.

20 is a baffle or partition rising from the

bottom plate of the igniter near the well and 21 is a baffle or partition depending from the top plate of the igniter near the front wall 22 of the raised portion thereof. These staggered baffles prevent the flame from striking back from the well through the igniter.

23 is a discharge nozzle which is secured horizontally in the front wall of the raised portion 17 of the igniter near the top of that wall and which is provided with a comparatively small discharge orifice 24, preferably about one-sixteenth of an inch in diameter, through which the liquid is delivered in a stream which is projected through the flame rising from the wick, as indicated in Fig. 1.

The pilot flame burns constantly and ignites the stream of liquid which is delivered by the nozzle and ignites the stream thoroughly so that the liquid is fully ablaze when it falls upon the snow, ice or other object, thereby preventing the fire from being extinguished by the chilling effect of the snow or ice and insuring the complete combustion and utilization of the liquid.

25 and 26 represent staggered baffles or partitions which are arranged in the rear portion of the igniter between the raised portion 17 and the rear wall 27 thereof and which prevent the flame from striking back through the rear portion of the igniter.

28 represents a plug which closes an opening formed in the bottom of the igniter for removing sand used in casting the same and for giving access to the igniter for cleaning.

In using this device for pouring a burning liquid upon the ice or snow on a switch or other object, the liquid flows from the pouring pipe through the igniter and fills all parts thereof by gravity, particularly when the pipe and igniter are held in a forwardly descending position, as is usually the case.

This improved igniter is safe and convenient in use, prevents the waste of liquid by reason of incomplete combustion, and is very effective in melting snow or ice.

I claim as my invention:

1. The combination with a can for containing an inflammable liquid and a pouring pipe which extends from the can and through which the liquid is adapted to be poured, of an igniter secured to the front end of said pipe and comprising a chamber having a pilot lamp at its front end, and a raised discharge nozzle arranged on said

- chamber at a sufficient distance in rear of said lamp to prevent the flame of the lamp from carbonizing the liquid on said nozzle and adapted to project said liquid from said chamber forwardly in a stream through the flame of said lamp. 5 front end a well and a wick tube above said well, a raised nozzle chamber extending upwardly from said main chamber in rear of said well, a nozzle in the front wall of said nozzle chamber, and means at its rear end for connection with a pouring pipe. 35
2. An igniter for an inflammable liquid comprising a main chamber having a pilot lamp at its front end, a nozzle chamber extending upwardly from said main chamber, and a discharge nozzle arranged in the front wall of said nozzle chamber and adapted to project said liquid forwardly from said nozzle chamber through the flame of said lamp. 10 40
- 10 3. An igniter for an inflammable liquid comprising a chamber having a pilot lamp at its front end, baffles arranged at intervals in said chamber, and a raised discharge nozzle arranged on said chamber in rear of said lamp. 15 45
- 15 4. An igniter for an inflammable liquid comprising a main chamber having a pilot lamp at its front end, baffles arranged at intervals in said main chamber, a nozzle chamber extending upwardly from said main chamber, and a discharge nozzle arranged in the front wall of said nozzle chamber and adapted to project said liquid forwardly from said nozzle chamber through the flame of said lamp. 20 50
- 20 5. An igniter for an inflammable liquid comprising a main chamber having at its 25 55
- 30 30

front end a well and a wick tube above said well, a raised nozzle chamber extending upwardly from said main chamber in rear of said well, a nozzle in the front wall of said nozzle chamber, means at the rear end of said main chamber for connection with a pouring pipe, and baffles arranged at intervals in said main chamber between said well and the rear end of said chamber. 55

6. An igniter for an inflammable liquid comprising a main chamber having at its front end a well and a wick tube above said well, a raised nozzle chamber extending upwardly from said main chamber in rear of said well, a nozzle in the front wall of said nozzle chamber, means at the rear end of said main chamber for connection with a pouring pipe, and baffles arranged at intervals in said main chamber between said well and the rear end of said chamber. 45 60

7. The combination with a can for containing an inflammable liquid and a pouring-pipe extending from said can, of an igniter secured to the front end of said pipe and comprising a chamber having a pilot lamp at its front end and a raised discharge nozzle arranged on said chamber in rear of said lamp and adapted to project said liquid from said chamber forwardly through the flame of said lamp. 60

Witness my hand in the presence of two subscribing witnesses.

JAMES GREER.
